UNITED STATES PATENT OFFICE.

WILLIAM J. GIBBONS, OF PHILADELPHIA, PENNSYLVANIA.

HOLDER FOR KNIVES, SPOONS, AND OTHER UTENSILS.

1,120,924.

Specification of Letters Patent. Patented Dec. 15, 1914.

Application filed January 26, 1914. Serial No. 814,282.

To all whom it may concern:

Be it known that I, WILLIAM J. GIBBONS, a citizen of the United States, and a resident of the city of Philadelphia, county of Philadelphia, State of Pennsylvania, have invented certain new and useful Improvements in Holders for Knives, Spoons, and other Utensils, of which the following is a specification.

10 My invention relates particularly to holders involving features of construction which are disclosed in my Patent No. 1,052,813, issued February 11th, 1913, and it has for its object to provide such holders with means whereby the same may be conveniently lifted by hand and carried without a tendency on the part thereof to swing into a position in which the base occupies an inclined instead of a horizontal plane.

20 In the construction, as shown in the accompanying drawings illustrative of my invention, it is necessary that when the holder is lifted it shall remain in normal position with its base occupying a horizontal plane 25 otherwise the knives, spoons, forks or any other character of utensil carried therein would likely slide from the holder.

In the drawings:—Figure 1 is a perspective view of a holder embodying my invention; Fig. 2 is a transverse section thereof; Fig. 3 is a perspective view of a modified construction of the same; Fig. 4 is a transverse section thereof; and Fig. 5 is a perspective view of still another modification 35 of the structure.

Referring to the drawings, 1 designates the rear side of a structure and 2 the ends thereof. The bottoms of the rear side and ends are connected by means of a board or plate 3 forming the base of the holder. The opposite or front side of the structure is open as illustrated. The space formed within the parts 1, 2 and 3 is divided into compartments by means of partitions 4 as shown.

In Figs. 1 to 4 inclusive a construction is illustrated in which such space is divided into two compartments while in Fig. 5 such space is divided into four compartments. Also in Figs. 1 to 4 inclusive the depth from front to rear of one of the compartments is greater than the depth of the other. The compartment of greater depth is adapted for holding knives or other utensils which are of greater length than utensils

such as forks or spoons which may be placed in the other compartment of less depth. In Fig. 5, however, all of the compartments are of the same depth from front to rear.

In the several forms of construction the bottom edges of the ends 2 and the partitions 4 are cut at an obtuse angle to the planes of such ends and partitions, that is, at an obtuse angle to the longitudinal axis of the holder, so that when the bottom 3 which is secured to such ends is resting upon a table or other horizontal support the holder leans or inclines to the rear. The tops of the ends and of the partitions, however, are cut along a plane at right angles 70 to the length of the said ends and partitions, that is, at a right angle to the longitudinal axis of the holder, as is illustrated in the drawings.

Each of the compartments of the holders is provided with inclined supports 5 upon which the articles or utensils which are placed therein are supported. The front ends of these supports are elevated, as shown, and incline from the front downwardly to the rear, such inclination being very clearly shown in Figs. 2 and 4 of the drawings. The portions of the compartments at the front side of the holders underneath the front ends of the supports 5 are 85 closed by means of closing plates 6 or equivalent means.

Although the supports 5 are preferably included in the construction, it will be understood that if such supports were removed 90 the front ends of the utensils would rest upon edges of the plates 6 and that the said utensils or articles would be inclined downwardly and to the rear in the several compartments and would, therefore, retain their 95 position therein so long as the holders are maintained with their bases in horizontal position, as when resting upon a table or other horizontal support.

By reason of the peculiar construction in 100 which the bottom or base 3 of the compartments occupies a plane forming an obtuse angle to the plane of the ends 2 and compartments 4 as described and in which the upper edges of the ends and compartments 4 are cut at right angles to the planes of such ends and compartments also as described, the holder when lifted is apt or tends to turn so that the base or bottom 3 occupies a position inclined with respect to 110

a horizontal plane while the top of the holder tends to assume a position with the top edges of the parts 2 and 4 in a horizontal plane. When, however, the holder occupies this position the knives, forks, spoons or other utensils therein, it has been found, slide out of the compartments.

In order to enable and permit the holder to be lifted and carried in its normal position as though it were resting upon a table or other horizontal support, I have provided parts of the top portion of the holder with a handle or hand-piece in which the portion thereof to be grasped by the hand is in parallel relation to the base or bottom of the holder.

In Figs. 1 and 2 I have shown such a hand-piece as consisting of a separate extension 8 secured to the plate 4. Such extension is generally speaking of triangular shape and is provided with an opening 10, the upper portion of which, between the points α — α , is substantially parallel to the base 3. This is the portion which is grasped by the hand when the holder is lifted. It is clear, therefore, that when grasped at this point and lifted the holder will remain in its normal position with its base in a horizontal plane.

In Figs 3 and 4 I have shown a construction in which the upper end of the division plate 4 is provided with a straight sided slot 12 parallel to the base 3. When a holder is lifted by placing the fingers through and grasping the upper side wall of a slot such as 12 it will be understood that the holder retains or remains in its normal position with its base occupying a horizontal plane.

In Fig. 5 a longer holder is provided rendering it desirable that the lifting means be situated at the opposite ends thereof. Accordingly, I have provided straight sided slots 13 in the opposite end plates thereof. The sides of these slots are parallel to the base 3 so that when the holder is lifted as above described with respect to the constructions illustrated in Figs. 1 to 4 inclusive the holder remains in its normal

position with its base occupying a horizontal plane.

In providing means whereby when the holders are lifted they maintain their normal positions in the manner above pointed out, the possibility of knives, forks, spoons or other utensils sliding accidentally from their respective compartments is reduced to a minimum.

I claim:—

1. A holder of the character described the base of which occupies a plane forming an obtuse angle with the body portion of the holder while the upper end of the said holder occupies a plane at right angles to the body portion of said holder and the said holder being provided with means whereby the same may be lifted which means is situated in a plane parallel to the base and forming an acute angle with the plane of the top of said holder. 70

2. A holder of the character described, consisting of a box-like device open at one side and provided with a division plate forming compartments, one of the said compartments being of greater depth than the other, and each of the said compartments being provided with means whereby when articles are placed therein their front ends are held in elevated position and the base of the said holder occupying a position in a plane forming an obtuse angle with the longitudinal axis of the said holder and the top of the said holder occupying a plane at right angles to such longitudinal axis and the said division plate being provided with means whereby when the said holder is lifted it is maintained in its normal position with its base occupying a horizontal plane such means including a part which is parallel to said base. 90

In testimony that I claim the foregoing as my invention I have hereunto signed my name this 24th day of January, A. D. 1914.

WILLIAM J. GIBBONS.

In the presence of—
HORACE D. REEVE,
CYRUS N. ANDERSON.
